FURNACE DOOR

Lawrence R. McAfoos, Pittsburgh, Pa., assignor to
 Reliance Steel Products Company, Rankin, Pa.,
 a corporation of Pennsylvania

Application May 11, 1937, Serial No. 141,907

2 Claims. (Cl. 122—498)

This invention relates to furnace doors of the type used in furnaces in which comparatively high temperatures are encountered, and particularly to those furnaces which are employed in heating and melting metals. In furnaces used for heating or melting metals, it is desirable to control the inflow of atmospheric air both as to place of ingress and as to quantity. Thus, it has been found that it is very undesirable, in general, to allow air to leak into the furnace around the furnace doors, as the effect on the heated metals of unknown quantities of air cannot be foreseen and this leads to metallurgical difficulties and loss of efficiency in the operation of the furnace. By preventing infiltration of air, it is possible to better regulate combustion with a consequent fuel saving and to better control the furnace operation which gives a superior product. It is also of importance that the heat of the furnace be conserved and leakage of heated gases around the edges of the furnace door prevented, as such leakage represents a direct heat loss, is injurious to the furnace structure, and increases the difficulties under which the workmen must labor. It is thus apparent that it is of advantage that the doors used in such furnaces be so designed and constructed as to prevent gas leakage into and out of the furnace.

In the commercial operation of furnaces, it has been found difficult to keep a reasonably tight seal between the furnace door and the furnace door frame, and especially is this true after the door or door frame has been in use for a short period of time.

I provide a door which has a thin projecting portion around the edges thereof, which projecting portion contacts the furnace door frame. The narrow edge will readily adjust itself to the contour of the door frame and provide a comparatively tight seal. If undue warping takes place either in the door or frame, or in both, the door can be removed and the projecting edges shaped to provide a satisfactory seal between the door edge and the frame. The edge can be readily renewed should the occasion arise by welding an appropriate strip around the edges of the door. By this construction, the furnace door can be made substantially gas-leak-proof, since it is much easier to form and maintain a seal between a narrow edge and a flat surface than between two flat surfaces. The disadvantages due to furnace door leakage can thus be avoided and the working conditions of the workmen and the operation of the furnace, and consequently, the product, will be improved.

In the accompanying drawing illustrating a present preferred embodiment of my invention:

Figure 1 is an elevation of a water-cooled furnace door; and

Figure 2 is a sectional view along the line II—II of Figure 1.

In the drawing, there is shown a water-cooled furnace door formed of rolled steel welded together at appropriate places and indicated generally by the reference character 3. The door 10 consists of an outer plate 4 and an inner plate 5, secured at its edges to the plate 4 by a weld 6. The main portions of the plates are separated from one another and secured at intermediate points by appropriate stay bolts 7. The plates 4 and 5 are shaped so as to provide between the main panel portions a main water space 8 and between the edge portions a peripheral water space 9, which extends around the periphery of the door and projects beyond the main water space 8. The plate 5 is shaped so as to provide a reentrant space 10, in which a refractory such as firebrick may be placed, if desired.

The outer plate 4 projects beyond the inner plate 5 and has a lip or sealing edge 11, which is comparatively narrow and which projects in a direction normal to the plane of the face of the door. The sealing or wearing edge 11 contacts the face of the furnace door frame (not shown) in which it may be mounted when the door is in position in the furnace. On account of the comparative thinness of the wearing edge, it is a simple matter to form a leak-proof seal with the door frame and should warpage occur, the sealing edge will readily adapt itself to the contour of the door frame. If unusual warpage occurs, the edges may be readily shaped as required by grinding or machining, to insure a tight contact with the flat door face of the door frame. In the event that the edge 11 wears to a point where it is substantially flush with the portion of the inner plate 5 nearest the furnace door frame, it is a very easy matter to replace or restore the projecting edge by welding an appropriate thin strip to the furnace door. Indeed, the projecting lip or wearing edge 11 may, in the first place, be formed by welding an appropriate strip to the furnace door instead of allowing the outer plate 4 to project, as shown.

A water inlet pipe 12 extends into one leg of the peripheral water space 9 to a point adjacent the lower side of the door. A discharge pipe 13 is also provided at the upper side of the door. The use of such circulation pipes is familiar and any desired arrangement of them may be adopted.

An opening 14 is provided through the door 2, 55

which opening is closed by means of a swinging cover 15, in which the usual peep holes 16 are formed. Lifting lugs 17 are secured to the upper side of the door.

5 While I have illustrated and described a preferred embodiment of my invention, it will be understood that it is not limited thereto, but may be otherwise embodied and practiced within the scope of the following claims.

10 I claim:

1. A furnace door comprising a main panel portion and a peripheral edge portion, said edge portion terminating inwardly in a comparatively thin wearing edge which projects in a direction normal to the plane of the face of the door so

that the edge is in position to slidably move along and to bear against a furnace door frame in which the door may be mounted.

2. In a water-cooled furnace door, an outer plate and an inner plate, said plates enclosing a main water space and a peripheral water space, and a thin wearing edge around the whole periphery of the door projecting inwardly in a direction normal to the plane of the face of the door from a point on the door adjacent the peripheral water space, so that the edge is in position to slidably move along and to bear against a frame in which the door may be mounted.
